UNITED STATES PATENT OFFICE.

WALDEMAR KOPS, OF NEW YORK, N. Y., ASSIGNOR TO KOPS BROS., INC., A CORPORATION OF NEW YORK.

ELASTIC WEBBING.

Application filed May 10, 1924. Serial No. 712,225.

To all whom it may concern:

Be it known that I, WALDEMAR KOPS, a citizen of the United States, residing in the borough of Manhattan, city, county, and

5 State of New York, have invented an Improvement in Elastic Webbing, of which the following is a specification.

My present invention relates to elastic webbing and more particularly to that type 10 of elastic webbing so woven as to produce alternate elastic and inelastic sections. The webbing made in accordance with my invention furthermore is that type of webbing in which the elastic strands are woven 15 into the fabric as wefts, this type of webbing being illustrated, for example, in Letters Patent No. 1,024,207, April 23, 1912 and Letters Patent No. 1,043,525, November 5, 1912. In weaving this type of webbing 20 is customary to inter-weave the elastic wefts and the inelastic wefts with the warp threads and in the weaving operation the elastic wefts are woven under a predetermined tension which is considerably less 25 than the elastic limit thereof in order that when released after the weaving operation the elastic wefts may contract to thus produce the elasticity of the webbing. It will be understood that in this form of webbing 30 the maximum stretch of the webbing is substantially that of the elastic wefts during the weaving operation. This is because of the inelastic wefts being of equal length with the elastic wefts during the 35 weaving operation and which consequently and as will be readily understood prevent the web from stretching beyond the extent to which the elastic wefts are stretched during the weaving.

40 The object of my present invention is to produce a web of the nature to which the invention relates and in which the stretch of the webbing is limited only by the maximum stretch of the elastic wefts employed. 45 In carrying out the invention the webbing made in accordance therewith is preferably constructed with inelastic marginal sections and an intermediate elastic section and in the weaving, as hereinafter more particularly 50 described, the elastic wefts are laid between the warps under tension in the elastic section of the web and the inelastic wefts in the elastic section are entirely removed or eliminated from the weaving and severed 55 adjacent the inner edges of the inelastic

sections after the weaving is completed so as to permit the web to stretch to the full extent of the elastic wefts employed.

In the drawing:

Fig. 1 is a plan of the obverse side of 60 an elastic webbing made in accordance with my present invention.

Fig. 2 is a plan of the reverse side.

Fig. 3 is a plan on an enlarged scale of 65 a portion of the reverse side.

Fig. 4 is a transverse section of the web after weaving, and

Fig. 5 is a section illustrating the web 70 after the unwoven inelastic weft threads have been cut therefrom.

In the drawings which illustrate my invention more or less diagrammatically, the usual inelastic warp threads are placed in the customary parallel relationship and are indicated at 10. The inelastic weft or filling threads are indicated at 11 and the elastic weft or filling threads are indicated at 12. In the weaving of the web the inelastic warp threads or the inelastic weft threads or both the inelastic warp and weft 80 threads may be closely spaced or crowded in the marginal portions of the web and the elastic weft threads looped on themselves and interwoven at the end portions thereof with the crowded warp and weft 85 threads to produce in the webbing inelastic marginal portions or sections A and B at the opposite edges of the web and an intermediate elastic portion or section C. It will be understood, however, that this arrangement of the elastic and inelastic section is only diagrammatic as the same may be otherwise arranged in the webbing as the intended use of the same may require. 90

As clearly illustrated in Figs. 1 and 2 95 of the drawing, the elastic wefts are so interwoven in the inelastic sections as to extend approximately one-half the way across the same; that is to say the inner portion of each inelastic marginal section A and B is 100 made with the elastic wefts interwoven with the inelastic wefts and warps, while in the outer portions of these marginal sections A and B the inelastic wefts and warps only 105 are interwoven and preferably this outer portion of these inelastic marginal sections is woven tubular. By this construction, as will be understood, a portion of the inelastic marginal sections is provided in which there are no elastic strands whatsoever so that 110

this portion of the marginal sections may be employed for sewing or otherwise attaching the webbing in position for use in a garment or other structure without puncturing or otherwise interfering with the elastic wefts or other elastic strands, although the elastic wefts as interwoven in the inner portions of the inelastic marginal sections is so tightly interwoven with the inelastic wefts and warps that when so punctured there is little, if any, detrimental effect in the elastic strands.

In weaving the web the elastic wefts are woven under a predetermined tension and in the inelastic sections of the web are interwoven with both the inelastic warp and weft threads, while in the elastic section of the web these elastic weft threads are interwoven only with the inelastic warps, the inelastic weft threads being removed by devices employed for this purpose in the loom so that the elastic wefts in the elastic section of the web are only interwoven with the inelastic warps. After the weaving operation is complete the inelastic weft threads are then cut or otherwise severed along the inner edges of the inelastic sections A and B and the adjacent edges of the elastic section C as for example along the lines D and E respectively.

It will now be understood that after the weaving operation the elastic wefts contract to their normal condition which determines the normal width of the web and that after the inelastic wefts have been severed or cut from the web as hereinbefore described the extent to which the web may be stretched is limited only by the elasticity of the elastic wefts employed and not to the extent to which the elastic wefts were stretched by the tension applied thereto during the weaving operation as is the case when both the elastic and inelastic wefts are interwoven with the inelastic warps in the elastic section of the web.

I claim as my invention:

1. In an elastic webbing having an elastic and an inelastic section, inelastic warp and weft threads, and elastic strands, all of which are interwoven in the inelastic section while in the elastic section the elastic strands are only interwoven with the threads running angularly thereto.
2. In an elastic webbing having inelastic marginal sections and an intermediate elastic section, elastic wefts and inelastic warps

and wefts, the said elastic wefts being interwoven with both the inelastic warps and wefts in the inelastic marginal sections and the elastic wefts being interwoven only with the inelastic warps in the intermediate elastic section.

3. In an elastic webbing having inelastic marginal sections and an intermediate elastic section, inelastic warps and wefts, elastic wefts, the said elastic wefts being interwoven with both the inelastic warps and wefts in the inelastic marginal sections and interwoven only with the inelastic warps in the intermediate elastic section.

4. In an elastic webbing having inelastic marginal sections and an intermediate elastic section, inelastic warps and wefts, elastic wefts, the said elastic wefts being interwoven with both the inelastic warps and wefts in the inelastic marginal sections and interwoven only with the inelastic warps in the intermediate elastic sections, the said webbing having no inelastic wefts in the intermediate elastic section thereby permitting the webbing to stretch to the elastic limit of the said elastic wefts.

5. In an elastic webbing having inelastic marginal sections and an intermediate elastic section, inelastic warps, elastic and inelastic wefts, with the elastic wefts in the intermediate elastic section being interwoven only with the inelastic warps and the elastic wefts being interwoven with both the inelastic warps and wefts in the inelastic marginal section but extending only part way into the same so as to provide a portion of the inelastic marginal sections in which there are only inelastic wefts and warps.

6. In an elastic webbing having inelastic marginal sections and an intermediate elastic section, inelastic warps and wefts and elastic wefts, the said elastic wefts being interwoven with a portion of both of the inelastic warps and wefts in the inelastic marginal sections to provide a portion of each of these sections in which the elastic wefts are interwoven and another portion of each of these sections in which none of the elastic wefts are interwoven, the said elastic wefts being interwoven only with the inelastic warps in the elastic section of the webbing.

Signed by me this 12th day of April, 1924.

WALDEMAR KOPS.
